DISPENSER

Frederick C. Schoening, New York, N. Y.

Application October 9, 1931, Serial No. 567,775

20 Claims. (Cl. 221—108)

This invention relates to improvements in dispensing and measuring apparatus, and particularly to an apparatus for dispensing material in powder form in predetermined or measured quantities, particularly such powders as are used for making chocolate drinks, malted milk, or the like.

An object of the invention is to provide means in such an apparatus for maintaining a progressive flow of the powder in the container, so that when a new charge is put into the container, the remainder of the previous charge will be disposed of first, and thus the contents can not accumulate and grow stale.

Another object is to provide a positive and effective means of stirring the dispensed material, and also of filling the charge measuring pockets.

A further object is to provide a dispenser of this character which is easily adapted to measure different quantities of powder up to a certain maximum quantity.

Finally, an object is to provide such a dispenser with means to prevent atmospheric moisture from entering it, which makes difficult the dispensing of certain kinds of material from the dispenser.

All these and other objects, as suggested herebelow, are attained by the method and means now to be described, and illustrated in the accompanying drawing, in which—

Figure 1 is a front elevation, partly in cross section, showing the completely-assembled dispenser with its main operating parts in fully assembled operative position.

Fig. 2 is a top sectional view through the line 2—2 of Fig. 1, but with the stirrer removed.

Fig. 3 is a mutilated top plan view, partly in section, through the line 3—3 of Fig. 1.

Fig. 4 is a top plan view of the guard plate shown in cross section in Fig. 1.

Like numerals refer to like parts throughout the several views.

The device consists essentially of an upright cylindrical container 10, Fig. 1, made preferably of sheet metal or other suitable material, and equipped with a suitable removable top or lid 11. Its bottom wall or guard plate 41 has two openings, as shown bounded by the numerals 12—13—14—15 and 16—17—18—19, Fig. 2.

Container 10 is removably mounted in a container holder 20, Fig. 1, which in turn is fastened to a heavy metal stand 21. The bottom wall of the container holder 20 has a discharge opening 22, Fig. 3.

A measuring wheel 24, Figs. 1 and 2, is positioned between container 10 and container holder 20. This wheel consists of a hub from which radiates a plurality of metal blades or arms. Wheel 24 is keyed to sleeve 25, Fig. 1, to the lower end of which is secured a ratchet wheel 26, Figs. 1 and 3, said sleeve being free to revolve about an inner shaft 39. When assembled, the arms of the measuring wheel 24 define a circular succession of pockets, as clearly shown in Fig. 2, which are adapted to be successively placed in register or alignment with the discharge opening 22. The step-by-step movement of the measuring wheel 24 and its attached ratchet 26, is accomplished by moving a hand lever 27 toward a stationary thumb rest 28, Fig. 3. By such movement, a pawl 29 which is spring-pressed inwardly by means of a small spiral spring (not shown) wound around it and anchored at each end in the usual manner, is caused to engage ratchet 26—which, by the way, has the same number of teeth as the measuring wheel has radial arms (in this instance nine)—to move it and its attached measuring wheel one intertooth space in the direction of the arrow, Fig. 3, to thus bring a measured quantity of the material to be dispensed into register with the discharge opening 22 of the container holder, to permit it to drop through by gravity. Thereafter the lever 27 is returned to its original position by means of a spring 30. The measuring wheel may be held against any possible back-lash movement by means of a spring 31, Fig. 3.

The bottom of container 10 has an inclined conical surface concentrically disposed and as shown clearly in cross section in Fig. 1.

The driving mechanism consists of three bevelled gears 32, 33 and 34. Gear 34 is rotatably mounted in a stationary horizontal bearing, not shown, but contained in the upper part of stand 21, said gear transmitting motion from gear 32 to gear 33 to turn the latter gear in a direction opposite to that of the former. Gear 32 is free to rotate with the measuring wheel 24 and ratchet 26.

Hand lever 27 is pivotally mounted on the hub of gear 32 and carries the pawl 29 which engages with the teeth of ratchet 26. When the lever 27 is moved by hand from its normal position as shown in solid lines in Fig. 3 to its dotted line position, pawl 29 moves the ratchet 26 one-tooth space in clockwise direction, looking down from the top. This brings the charge carrying pocket 24a, Fig. 2 into discharge position 24b, where a

tumbler or other container placed underneath receives the charge of dispensed material.

Simultaneously with this movement of the measuring wheel gear 32 also turns gear 33 in an opposite direction through the intermediate gear 34 to in turn rotate shaft 39 extending upwardly through sleeve 25. Shaft 39 in turn is keyed to a stirring member 35, disposed above the guard 41 and through which the material 10 drops into the pockets of the measuring wheel. Hence, shaft 39 turns the stirrer 35 in an opposite direction or counterclockwise looking down from above.

By its movement, this stirring member, which 15 includes a plurality of thin arms extending from a central portion thereof, sweeps the material off the conical surface and also the horizontal surface of said guard plate 41, the latter being stationary and separating the material in the 20 container from the pocket in the discharge position so that only the material in the pocket is discharged. The stirrer also deposits the powder into the other pockets of the measuring wheel 24.

Pivoted on the shaft or sleeve 25 of bevel gear 25 32 and resting on the floor of holder 20 is a shutter plate 36. A portion of this plate is cut out to conform with the discharge opening 22 in the holder. In the normal position of the lever 27, this opening of the shutter plate is out of register with the discharge opening. In this position it makes an air-tight seal, preventing atmospheric moisture from entering the container; and this is important in the operation of the device, since any moisture that is permitted to enter is readily absorbed by the powder, making it sticky and therefore difficult to handle and dispense. A collar 37 on pin 38 of the hand lever 27 engages in a hole of the shutter plate 36 and moves it so that when the lever 27 is in the dotted 30 line position, the opening of the shutter plate is in register with the discharge opening 22 in the holder 20, thus permitting the measured quantity of the powder to fall through. The connecting collar 37 moves back and forth in a clearance 45 slot in the floor of the holder 20 (Fig. 1). Immediately upon the release of the handle 27, its spring 30 returns it to its normal position, and also brings the shutter opening out of register with the discharge opening, thus closing the 50 opening effectively.

It will be apparent from this construction that a further great advantage of the dispenser is the easy way by which it may be adapted to measure different quantities of powder. For instance, by simply substituting a spacer ring 42, and a measuring wheel of different width, any desired quantity can be measured, using the same style dispenser.

It is to be understood that the present disclosure is for the purpose of illustration only, and that the invention is not limited thereto. To those skilled in the art, many modifications of the invention will be readily apparent, and it will also be obvious to such skilled persons that part of the method and means may be used without other parts thereof, many such combinations of the parts readily suggesting themselves. Therefore, it should be, and is to be distinctly understood that for a definition of the limitations of the invention, reference must be had to the appended claims.

Having now described the invention, what is claimed as new and for which Letters Patent of the United States is desired, is:—

1. A dispenser for powder-like material includ-

ing a container, a floor therein, said floor having an aperture therein through which the material may pass, a fixed cone-shaped element pointing upwardly and located in the lower part of the container, and a stirrer element located above the cone element to wipe the material from the cone and from the floor to said aperture.

2. A dispenser for powder-like material including a container, a floor therein, said floor having an aperture therein through which the material may pass, a fixed cone-shaped element pointing upwardly and located in the lower part of the container, a stirrer element located above the cone-shaped element to wipe the material from the cone and from the floor to said aperture, a closure for said aperture, and means to actuate said closure to open said aperture.

3. In a dispenser for powder-like material, the combination of a container, a horizontally disposed measuring wheel beneath said container, a guard arranged above said wheel, a cone-shaped member on said guard, said guard having an aperture therein, a scraper arranged to scrape the material from the cone and the guard plate to discharge it through said opening, said measuring wheel having a plurality of compartments arranged to receive the material from the container through the aperture in said guard, and means whereby the material may be discharged successively from said compartments.

4. In a dispenser, a container having a horizontal bottom portion with a discharge aperture therein, a measuring wheel placed beneath the container and adapted to receive material through said aperture, a container holder adapted to support the container and also the measuring wheel, and having one discharge opening, a part of the container bottom forming a shield plate over the discharge opening in said container holder, and a shutter for said discharge opening, said shutter being located between the measuring wheel and the bottom of the container holder.

5. The invention as in claim 4, including a stirrer for the material to be dispensed, and means for actuating it in a direction opposite to the movement of the measuring wheel and simultaneously with said movement, while discharging the material from the dispenser.

6. The combination in a dispenser of a container, a holder therefor, a measuring wheel positioned between them and having a plurality of charge carrying pockets, means for rotating the measuring wheel, a stirring member positioned over the measuring wheel, and a guard between the stirring member and the measuring wheel, said guard having an upstanding conical central portion and a surrounding horizontal portion.

7. The invention as in claim 6, including means for rotating the measuring wheel manually a predetermined distance, and other means associated therewith for simultaneously rotating the stirring member in an opposite direction.

8. The combination in a dispenser of a container, a bottom therefor having an aperture, an upstanding conical surface centrally disposed in the container bottom, stirring means adapted to be rotated over said container bottom, a measuring wheel positioned beneath said bottom, means for manually moving the measuring wheel and stirring means simultaneously in opposite directions, said means including a manually operated lever adapted to be moved a predetermined distance in one direction and containing spring

- means adapted to return it to normal position when released.
9. The invention as in claim 8, including a container holder having a discharge opening, a closure plate over the discharge opening, and means adapted to move said plate to close said opening while the manual lever is being operated.
10. In combination, a container having a discharge opening, a holder therefor, a measuring wheel positioned in the holder and beneath the container, a stirrer positioned above the measuring wheel, a bevel gear and a ratchet secured to a sleeve to move with the measuring wheel, an intermediate gear in mesh with said bevel gear, a second gear in mesh with the intermediate gear and secured to the central shaft projecting upwardly through a central hole in said sleeve, and through the measuring wheel to the stirrer, said shaft being adapted to rotate in a direction opposite to the measuring wheel, and lever means adapted to be operated manually in one direction, and a pawl on the lever means adapted to engage the teeth of the ratchet to turn said ratchet and the first mentioned gear a predetermined distance.
11. The invention as in claim 10 including means for returning the manual lever means to original position when released.
12. The invention as in claim 10 including means for closing the discharge opening in the container holder by movement of said lever means.
13. In a dispenser for powdered material, the combination of a supply chamber, a measuring element in the bottom of said chamber, a stirrer located immediately above said element, means located beneath the measuring wheel to rotate said measuring wheel, means extending from beneath the measuring wheel to the stirrer to rotate said stirrer relatively to the measuring wheel, and means whereby a measured quantity of material may be discharged from the dispenser.
14. In a dispenser for powdered material, the combination of a supply chamber, a measuring element in the bottom of said chamber, a stirrer superposed on the measuring element, driving means connected to the bottom of the measuring element to rotate said measuring element, means extending upwardly through said driving means to rotate the stirrer relatively to the measuring element, and means including a finger-piece whereby a measured quantity of the material may be discharged from the dispenser.
15. In a dispenser for powdered material, the combination of a supply chamber, a measuring element in the bottom of said chamber, a stirrer located immediately above said element, means to support the measuring element and the stirrer to rotate about a common axis, means located beneath the measuring wheel to rotate said measuring wheel, means extending from beneath the measuring wheel to the stirrer to rotate said stirrer relatively to the measuring wheel, means including a finger piece whereby a measured quantity of material may be discharged from the dispenser, and means operable by the last mentioned means to actuate both of said rotating means.
16. In a dispenser for powdered material, the combination of a supply chamber, a measuring element in the bottom of said chamber, a stirrer located immediately above said element, means including a shaft connected to the bottom of the measuring wheel to rotate said measuring wheel, means including a shaft extending through the first mentioned shaft to rotate the stirrer relatively to the measuring wheel, means having a discharge opening therein and located under said measuring element, a shutter to normally close said aperture, and means to actuate said shutter to discharge a measured quantity of material and to actuate both rotating means.
17. In a dispenser for powdered material, the combination of a supply chamber, a measuring element in the bottom of said chamber, a stirrer superposed on the measuring element, driving means extending upwardly to the measuring element to rotate the latter, driving means extending upwardly through the first mentioned driving means to rotate the stirrer, means including a discharge opening and located under said measuring element, a shutter to normally close said aperture, means to actuate said shutter to bring an aperture therein into register with the first mentioned aperture to discharge a measured quantity of material, means associated with the actuating means to operate one of the driving means, and means connecting the latter with the other driving means.
18. In a measuring dispenser for powdered material, the combination of a supply chamber, a rotatable measuring wheel in the bottom thereof, said wheel having a central portion and arms extending therefrom to form measuring pockets, a stationary cone-like member supported above and independently of the central portion of said wheel to shed the material into the pockets, means for scraping the material from the cone-like member, and means whereby the material may be discharged from one of said pockets.
19. In a measuring dispenser for powdered material, the combination of a supply chamber, a rotatable measuring wheel in the bottom thereof, said wheel having a central portion and arms extending therefrom to form measuring pockets, a stirrer superposed on the measuring wheel and rotatable relatively thereto, a fixed cone-like element located over the central portion of said wheel to shed the material into the pockets, and an arm integral with and extending horizontally from the edge of the cone-like element and over a part of the pocket portion of the wheel, and means whereby the material may be discharged from one pocket at a time.
20. In a dispenser, the combination of a casing, a rotatable measuring wheel therein, said measuring wheel comprising a hub and arms radially disposed thereon to form pockets, and a spacer ring in said casing to surround said wheel, said casing having an aperture through which the material may be discharged from any one of the pockets, said ring and said wheel being replaceable by similar ones of different dimensions to vary the quantity of material discharged from the dispenser.

FREDERICK C. SCHOENING.
